(57) **CLAIM**

The ornamental design for a power plug cover, as shown and described.

DESCRIPTION

FIG. 1 is a rear perspective view of a power plug cover showing my new design;

FIG. 2 is a front perspective view thereof;

FIG. 3 is a front elevational view thereof;

FIG. 4 is a rear elevational thereof;

FIG. 5 is a left side elevational view thereof;

FIG. 6 is a right side elevational view thereof;

FIG. 7 is a bottom plan view thereof; and,

FIG. 8 is a top plan view thereof.

The fragmentary broken-line disclosure of plug and power cord in FIG. 1 represent unclaimed subject matter provided for illustrative purposes only and which form no part of the claimed design.
